William Woodbridge

Sisters Patent

The defendant reposes in the Sisters Patent and the following part of the same contains a description in the words of the late William Woodbridge, witness of his improvement in the mode of tipping out and other carriage wheels.

It was this tipping of the wheels of carts and other wheel carriages that has been highly inconvenient and unsafe in roads, detours, mountains and circumstances in which they are driven up and down hills and in closed places to secure them and their teams, and the loads and passengers from injurious accidents, to ride in the working of horses while drawing heavy loads, to roll in plowing loads, jowls, loads and other loads except when they are being driven up and down hills to the right or left of the rotations of a wheel on one side of them. Passenger is tripped; horses Violent shock upon the team when going down hills and may be conviniently and safely staffaged as a security against the injury of stage and other carriage steep when the horses are transferred to them and the horses are otherwise deemed. There is no other method of tipping the carriage wheels but that they are driven up and down hills as believed by the subscribers that of applying horses abstinent to the periphery of the wheel to proceed in rotation on the axis tried.

Therefore to all persons to whom these presents shall come, it is known that William Woodbridge, of the Town of Hallowell in the County of Kennebec, and State of Maine, Merchant, has invented, constructed, made and applied to the carts and passenger carriages in the mode of tipping out and other carriage wheels by means of a ring or roller, which, fitted on the periphery of the exterior ends of the hubs of the cart or carriage wheels, and a rank kept on hand according to the use to be

or by means of volutes or rays, on the hubs of the wheels and the crank slips or cones deemed best to be used. The ray is represented as being fixed upon the hub by the part marked A in Figure 1 on the inner end, bearing and conveniently made of iron and brass on the hub in the form of hoop, or being formed by volutes in the hub covered with hoop a short way.

The ray is used when it is desired to stop or stay the wheel from turning on the way only for protection from turning backwards and when the ray is used, the crank slip may lay upon and play on the ray without stopping the wheel from turning forward, but the ray in this case protects the crank slip and prevents the wheel from turning back. The crank slip or head is marked B on figure 2, and is secured to the axlebox by a strong iron strap (marked C) in which strap is a slot not to hold the end of the crank slip inserted into it and in which slot it may be held instead of the ray. And when it is desired to have the wheel run free within the ray the crank slip may be held upon the way of the ray of the hub by a stop on the body of the carriage or the frame.

A hub with rays or volutes is represented by Figure 3 in the drawing, and is most conveniently made in the form of an iron hoop covered with rays. The form of the crank slip may be of the same form as the one used with the rays; and may be secured to the axlebox in the same manner as above. It will not, and may be held off from the hub in the same manner when not in use, but the crank slip may be permitted to play on and the ray on the hub without being held off, in a direction opposite to the motion of the wheel, if the end of the crank slip be playing around on the ray to make as represented at A, in figure 2, that is to say, that when being brought near of a wedge form on the outer side protecting the rays left out in the hub when being on the rays of the hub, opposite to the motion of the wheel, but when placed on the hub in the direction of the motion of the wheel it will not be able to stop the wheel. One of these crank slips can open each side of the axlebox, excepted upon it when it is intended to stop the wheel from turning either way.

means of the crank step and cog. When cast iron bands are used the cog and the cog may be cast in iron upon the bands. The figure 5 on the covered drawing is a pair of cast wheels, with the straight or long arm forward to indicate the position of the wheels in the carriage and exhibits on the wheel marked K a sag and the position of the crank step when lifting the wheels from running barkments. When there is no body of the carriage to interfere one crank step placed on a near the ^{top} of the carriage will answer the purpose to stop the wheel from running either way when applied to the cog and by taking out a brick ^{pin} and removing the wheel a little the crank steps may be taken out of the sockets of the steps and laid aside of the wheels or carriages are employed in any business where the big is not wanted.

Witnessing that the above is a true Specification
of my said Improvement as above described & have caused set my hand
this fifteenth day of March in the Year of our Lord one thousand eight
hundred and thirty six.
